United States Patent Office.

CHARLES R. TOMPKINS AND JOHN WRIGHT, OF ROCHESTER, NEW YORK.

Letters Patent No. 77,129, dated April 21, 1868.

IMPROVEMENT IN SAW-MILLS.

The Schedule referred to in these Letters Patent and making part of the same.

TO ALL WHOM IT MAY CONCERN:

Be it known that we, CHARLES R. TOMPKINS, of the city of Rochester, county of Monroe, and State of New York, and JOHN WRIGHT, of the city, county, and State aforesaid, have invented a new and useful improvement in the Manner of Feeding Resawing-Machines; and we do hereby declare that the following is a full, clear, and exact description of the construction and operation of the same, reference being had to the annexed drawings, making a part of this specification, in which—

Figure 1 is a perspective view.

Figure 2 is a plane or top elevation with rollers removed.

Figure 3 is a sectional view of the movable saddle with the gears removed.

The nature of our invention consists in constructing a resawing-machine in the ordinary manner, with a bed-plate, *k k*, figs. 1 and 2, securely bolted to the frame *o*, fig. 1. This bed-plate is provided with suitable ways, into which the sliding piece, *c c*, fig. 1, and *c c c c*, fig. 2, is locked, by being planed to a corresponding angle.

This sliding piece, *c c*, fig. 1, is worked either way, by means of the screw and hand-wheels, *f*, fig. 1, and *f f*, fig. 2.

Upon this sliding piece, *c c c c*, fig. 2, is a hub, *l*, fig. 3, and is turned off so as to fit to a hole in the movable saddle *d*, fig. 3, and to allow it to swing upon this centre.

Upon plate *C C*, fig. 3, are attached nuts, *2 2*, into which the thumb-screws, *H H*, fig. 3, are fitted, so that the ends of them press against the sides of the saddle, *d*, fig. 3, and when one is turned to the right and the other to the left, the saddle *d*, fig. 3, is moved or made to turn upon the centre at *l*, fig. 3, or in the opposite direction by reversing the screws.

To this saddle *d*, fig. 3, are attached suitable bearings, *3 3*, fig. 3, and *3*, fig. 1, into which the shafts of gears *i i i i*, fig. 2, are fitted and revolve.

Upon this saddle *d*, figs. 1 and 3, the arms *a a*, figs. 1 and 2, are fastened by the screws *n n*, fig. 1, and *n n*, fig. 2, and are provided with slots, so that they may be moved either forward or back, and, by so doing, the top of the rollers, *b b b b*, fig. 1, may be inclined to any angle, or set square with the saw *G*, fig. 1.

The tops of arms *a a*, fig. 1, branch off, so as to form a support to both rollers, as shown at *l l l l*, fig. 1, and are attached to the boxes *x x x x*, fig. 1, which form a joint upon the pins or bolts *y*, fig. 1.

The lower end of the shaft that passes through rollers *b b b b*, fig. 1, rests in the centre of gears *i i i i*, figs. 1 and 2, and are so arranged that the rollers may be inclined to any angle without altering the position of gears *i i i i*, figs. 1 and 2.

The rollers *b b b b*, fig. 1, and gears *i i i i*, figs. 1 and 2, are driven by a cross-shaft and bevel-gears, in common with all similar machines.

The other parts of the machine being common to all machines of this kind, a description is unnecessary.

In order to operate the aforesaid improvement, the operator, after adjusting the rollers with reference to the saw, either for straight or bevel-sawing, brings them to the proper distance apart by means of screws and hand-wheels *f f*, fig. 1. The board to be resawed is then fed to the saw *G*, fig. 1, resting on the plate *4*, fig. 1, and between rollers *b b b b*, fig. 1.

One pair of rollers remain fixed, except when they are moved by hand-wheel *f f*, fig. 1. The opposite pair is provided with a spring or lever, so arranged that should the board vary in thickness, the rollers may adapt themselves to it, and maintain a uniform pressure, but, should the saw incline to either side of the board, as is often the case just before or after filing, the operator moves one of the thumb-screws *H H H H*, fig. 1, on the side opposite the spring, and thereby changes the direction of the saw, by moving the rollers which carry the board to one side of the saw, or the reverse, if necessary. This enables the operator to have complete control of the saw while in operation.

The saddle *d*, fig. 3, is held down to plate *C C*, fig. 3, by the screws *J J*, fig. 3, but not so as to prevent it from moving in the slots.

What we claim as our invention, and desire to secure by Letters Patent, is—

The movable saddle *d*, turning on the hub *l*, and adjusted by the set-screws *H H* and the slots *J J*, with their confining-screws, all adjusted to operate substantially as described.

CHARLES R. TOMPKINS,
JOHN WRIGHT.
